ELECTRIC HEATER

Melbourne Jack Eno and Wilbur Earl Eno, both of 6421 SW. 42nd Terrace, Miami, Fla. 33155

Filed Aug. 30, 1967, Ser. No. 8,432

Term of patent 14 years

(Cl. D23—93)

 which is the same as viewed from either side;

We claim:

The ornamental design for an electric heater, as shown and described.
